(57) **CLAIM**

The ornamental design for an inflatable pad pattern, as shown and described.

DESCRIPTION

FIG. 1 is a first embodiment front perspective view of our new design for an inflatable pad pattern;
FIG. 2 is a top view thereof;

FIG. 3 is a front view thereof;

FIG. 4 is a left side view thereof, the right side view being a mirror image; and

FIG. 5 is a bottom view thereof.

FIG. 6 is a second embodiment front perspective view of our new design for an inflatable pad pattern;

FIG. 7 is a top view thereof;

FIG. 8 is a front view thereof;

FIG. 9 is a left side view thereof, the right side view being a mirror image; and

FIG. 10 is a bottom view thereof.

FIG. 11 is a third embodiment front perspective view of our new design for an inflatable pad pattern;

FIG. 12 is a top view thereof;

FIG. 13 is a front view thereof;

FIG. 14 is a left side view thereof, the right side view being a mirror image; and,

FIG. 15 is a bottom view thereof.

The broken lines depict portions of the inflatable pad pattern that form no part of the claimed design.
